UNITED STATES PATENT OFFICE.

CARL BRAUN, OF CANASTOTA, NEW YORK.

RECEPTACLE STERILIZER.

Application filed May 12, 1923. Serial No. 638,547.

This invention relates to sterilizing devices and has more special reference to a device for sterilizing and drying receptacle parts, more especially milk can parts.

Conventionally receptacles of this character are subjected to sterilization generally a treatment in a steam bath, and are then dried by directing an air blast against or into the receptacle part, the condensed steam being evaporated by the air blast. This method of drying is to a certain extent objectionable in that the air blast which is projected against the receptacle part simply evaporates the fluid portion of the condensed sterilant, leaving any residue deposited on the receptacle part. Not only is the residue of the sterilant "caked" on the receptacle part by the methods heretofore in use but the air blast because of admixture with the outer air is not bacteriologically inert and to a certain extent undoes the effect of the sterilization.

One of the principal features of the present invention has reference to an improved drier in which the drying operation is effected by creating a vacuum to withdraw the condensed sterilant and thereby simultaneously remove any matter which may be suspended in the condensate in contradistinction to the drying methods heretofore in use in which the suspended matter is "caked" on the receptacle part.

In its more specific aspect the required suction is achieved by an aspirator operated by a steam jet, the steam for the jet being obtained from the sterilizing conduit, thereby affording a simple and compact arrangement of the device.

While but one embodiment of the invention is disclosed in the accompanying drawing it is to be understood that this embodiment merely serves as an illustration of the underlying principles of the invention so that it may be readily comprehended by those skilled in the art and is not intended as limiting the invention to the specific form disclosed therein.

In said drawing:

Fig. 1 is a side elevation of the invention partly fragmentary and partly in section.

Fig. 2 is a section of Fig. 1 on the line 2—2.

Continuing now by way of a more detailed description, a hooded table or platform A supports a plurality of steam sterilizing devices B and C carried by a pair

of preferably parallel brackets E longitudinally disposed with respect to the platform A and slightly raised therefrom, so that the drippings from the can covers will be accumulated thereon and may be collected for disposal. This pair of brackets also carries a water rinsing device F, the rinsing and the sterilizing devices preferably being located in a straight line, the former being located near one end of the table so that the receptacle parts as they are started from one end of the table are subjected to a thorough rinsing before being subjected to the sterilization. This rinsing is accomplished preferably by subjecting the receptacle part to a spray of water which may be and preferably is heated so as to increase its solvent effect. In order that the water jets may acquire the requisite velocity to displace any particles of extraneous matter adhering to the receptacle part, the water is introduced into a chamber or spray nozzle G having a plurality of perforations G' through a water inlet pipe H at a sufficient pressure, so that the upwardly projected jets normally rising from the spray nozzle strike the receptacle part with a sufficient impact to effect a thorough rinsing.

In order to insure a rinsing of both sides of the can cover, the pipe H has a perforated extension piece H' having one end connected to a T coupling H'' and its other end closed by a cap J. The portion of the pipe H overhanging the spray nozzle G is also preferably perforated to insure a curtain of descending water for substantially all parts of the receptacle part to be treated. In order to obviate delivery of rinsing fluid when not required, a valve K normally intercepts the flow in the pipe H and has a dependent movable arm K' so arranged with respect to the rinsing pan G that the receptacle part lifts the arm when in proper position to receive the rinsing bath.

It is contemplated first subjecting the receptacle part (specifically a milk can cover) to a rinsing operation, as above indicated, and then to two sterilizing operations. Each of the sterilizing devices B and C comprise a perforated chamber or spray nozzle L similar to the rinsing spray nozzle G and is controlled by receptacle cover operated valves M having dependent arms M' similar to the valve K. These valves normally intercept the steam in pipes N to avoid waste of the steam. The steam pipe N also furnishes the

requisite power jet for an aspirator O which affords the means to create the necessary vacuum on an auxiliary drying plate P. The aspirator O comprises a high pressure steam nozzle P' fed by pipe T connected to steam pipe N and adapted to discharge into a waste pipe P'' of somewhat larger diameter than the diameter of the nozzle and create a suction in the flared drain Q communicating with the plate P on which the can cover is adapted to fit rather snugly. The suction device P' is maintained normally in operation by a valve T' having a depending trip arm T'' similar to and functioning in the same manner as valves M and K.

In order that the cans may be progressively advanced over the rinsing, sterilizing and drying devices, a pair of oppositely disposed guide rails R are supported in any convenient manner and are spaced sufficiently to receive the receptacle object. These rails are fastened to the table in any convenient manner as for example by bowing the ends, these bowed ends forming a desirable flare to facilitate the insertion of the covers in the runway formed by the spaced rails. In order that the covers may be progressively advanced over the cleaning devices, a manually operable retractile rod S having a plurality of dependent arms S' is slidably carried in suitable brackets, the dependent arms being adapted to engage

the covers and on movement of the rod to advance them in the guide rails R from one end of the device to the other end. The can covers are ejected at the rear end of the runway after the completion of the drying operation and may be caught in a suitable receptacle.

The dependent arms S' are arranged in pairs on opposite sides of the rod S and are connected by a cross-member or stop S''. This stop permits the dependent arms to swing in a counter clockwise direction so that when the rod S is retracted the arms will drag over the covers.

It is claimed:

A device for drying milk can parts comprising a perforated horizontal plate adapted to receive the parts, a flared drain dependent from the perforated plate and connecting therewith, a waste pipe connected with the lower end of a drain, an aspirating nozzle of restricted diameter adapted to blow into the waste pipe and create a partial vacuum in the flared drain and the can part to dry the latter, and means cooperating with the milk can part to operate said nozzle when the can part is placed in position on the perforated plate.

Signed at Canastota, in the county of Madison and State of New York, this 29th day of April, 1923. A. D.

CARL BRAUN.
